UNITED STATES PATENT OFFICE

FRANCIS D. SWADER, OF NEAR CROMWELL, OKLAHOMA

ROUNDABOUT

Application filed July 29, 1929. Serial No. 381,883.

This invention appertains to new and useful improvements in amusement devices, and more particularly, to a novel roundabout apparatus.

5 The principal object of this invention is to provide a novel roundabout wherein the same may be actuated by the passengers carried thereby.

Another important object of the invention is to provide a roundabout which because of its simple construction can be manufactured and sold at a reasonable cost.

10 These and numerous other important objects and advantages of the invention will become more apparent to the reader after considering the invention as described and claimed hereinafter.

In the drawings:

20 Figure 1 represents a top plan view of the novel apparatus.

Figure 2 represents a fragmentary vertical sectional view taken substantially on line 2—2 of Figure 1.

25 Figure 3 represents a fragmentary side elevation of the apparatus.

Referring to the drawings, wherein like numerals designate like parts, it will be seen that the invention includes a pedestal 5 having bolts 6 anchored at their heads within a 30 suitable foundation 7 projecting upwardly through openings therein with nuts 8 serving to prevent displacement of the pedestal from the said bolts.

35 The upper end of the pedestal is constructed to provide a hub 9 into which the lower tapered end of a post 10 is secured by a key 11. The lower end of the post is also reduced and threaded to receive a nut 12 whereby the post may be firmly maintained 40 in a perpendicular position with respect to the foundation 7 and against rotation.

45 Circumscribing the post 10 is a sleeve 13, which is counter-bored at its lower end to receive a bushing 14 on the lower reduced portion of the post 10, while interposed between the lower end of the sleeve 13 and the hub 9 of the pedestal 5 is a ball bearing structure 15. A lubricant containing cup 16 is also supported by the upper end of the pedestal 5 for constantly maintaining the

bearing structure 15 lubricated. The lower portion of the sleeve 13 is provided with a pair of circumferentially extending flanges 17—17.

The upper end of the sleeve 13 is counter-bored to receive a wear bushing 18 which circumscribes a reduced portion of the post 10. A table-like structure 19 is provided at the upper end of the sleeve 13 and this is provided with an upstanding circumferentially extending flange 20 at its periphery. The upper end of the post 10 projects upwardly within the confines of the flange 20 and has a bevelled gear 21 suitably keyed thereto.

55 A housing 22 is provided for the gear 21 while disposed journally through the housing 22 at equal circumferentially spaced intervals are the stub shafts 23, each of which is provided with a bevelled gear 24 at one 60 end for mesh with the gear 21. The opposite end of each stub shaft 23 is journalled through an opening in the flange 20.

65 As is clearly shown in the drawings, an annular passenger supporting platform 25 is provided with a vertical wall 26 at its inner edge. This vertical wall is provided with a ledge or shoulder 27 which affords an 70 arm rest for the passengers.

75 At suitable points, rigid straps 28 follow the contour of the platform 25 and vertical wall 26 and projects inwardly toward the gear 21 at its upper end, as denoted by numeral 29. Brace bars 30 are connected at their inner ends to the table leg structure 19, while 80 their outer ends are secured to the inwardly disposed upper ends of the straps 28. Additional brace bars 31 have their upper ends secured to the end portions 29 of the straps 28, while their lower ends are secured between 85 the flanges 17—17 by means of bolts 32.

85 A third set of brace bars 33 have their outer ends secured to the bottom side of the platform 25, while their inner ends are secured to the lowermost flange 17 by means 90 of the aforementioned bolts 32.

95 A ring 34 is mounted upon the brace bars 30 at their outer ends and suitably secured thereto. Mounted upon the ring 34 are bearings 35, and disposed through openings in 100

the bearings 35 at equal circumferentially spaced intervals are the shafts 36, each provided with a crank handle 37 at its outer end and being connected at its inner end by means of a flexible coupling 38 to a corresponding stub shaft 23.

5 Mounted upon the platform 25 at suitable spaced intervals and adjacent each crank handle 37 is a seat 39 on which the passenger sits.

10 It will thus be seen that the passenger in rotating the shaft 36 will cause the gear 24 to travel on the gear 21, thus imparting motion to the platform 25.

15 Obviously, in the manufacture of this novel roundabout apparatus, various changes in the specific shape, size and materials may be resorted to without departing from the spirit and scope of the invention as claimed herein-after.

20 Having thus described the invention, what is claimed as new is:

An amusement device comprising a stationary post, a sleeve rotatably mounted on said post and having upper and lower sets of flanges, a stepped annular platform concentrically disposed with respect to said post, a plurality of rigid reinforcing straps secured to said platform on the underside thereof and in relatively spaced points, said straps conforming to the contour of the stepped platform and having their respective upper ends disposed inwardly to provide brackets, a plurality of brace bars connected to said upper flange and the upper portion of said reinforcing strap, a plurality of spaced brace bars connected to said lower flange at the lower portion of said platform, a diagonally extending brace bar connected to the lower flange and the upper portion of the platform, a ring extending horizontally of said brace bars and secured thereto adjacent the upper edges of the said stepped platform, said ring being disposed in overlapping relation with respect to the bracket portions of the reinforcing strap and being provided at certain circumferentially spaced points with vertically disposed bearings, a plurality of crank shafts extending radially of the said post and respectively supported adjacent their outer ends in a bearing of the said ring, operating handles on the outer end of said crank shaft, seats disposed on a step of said platform adjacent the crank shaft, and a gearing connecting the inner end of the crank shaft with the said post.

In testimony whereof I affix my signature.
FRANCIS D. SWADER.
